UNITED STATES PATENT OFFICE.

MONTROSE P. HYNSON, OF ST. LOUIS, MISSOURI.

DESIGN FOR A STOVE.

SPECIFICATION forming part of Design No. 30,142, dated February 7, 1899.

Application filed January 12, 1899. Serial No. 701,992. Term of patent 14 years.

To all whom it may concern:

Be it known that I, MONTROSE P. HYNSON, of the city of St. Louis, State of Missouri, have invented a new and original Design for a 5 Stove, of which the following is a full, clear, and exact description, reference being had to the accompanying drawings, forming a part thereof.

Figure 1 is a top plan view of a stove showing my new design. Fig. 2 is a side elevation of the stove.

As shown in the drawings, the leading or material feature of my design consists of the rectangular body 1, having a projection 2 extending laterally from its front lower edge, and extending laterally from its rear side is a cylindrical body 3. On top of the body 1 appears the circular plate 4, having a bev-

eled edge 5, and extending upwardly from the center of this plate is the cylindrical body 6, 20 surmounted by the flange 7, on top of which is formed a plurality of ribs 8. Wedge-shaped ribs 9 extend from the plate 4 upwardly a short distance upon the cylindrical body 6, said ribs being arranged equal distances apart 25 and at right angles to each other.

I claim—

The design for a stove, substantially as herein shown and described.

In testimony whereof I affix my signature 30 in presence of two witnesses.

MONTROSE P. HYNSON.

Witnesses:

M. P. SMITH,
A. J. McCUALEY.
